(57) **CLAIM**

The ornamental design for a thermally insulated container, as shown and described.

DESCRIPTION

Priority is being claimed to copending U.S. patent application Ser. No. 12/319,465 filed Jan. 7, 2009.

FIG. 1 is a top, left perspective view of the thermally insulated container showing my new design.

FIG. 2 is a top right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top, left perspective view thereof in an alternate position;

FIG. 10 is a top, right perspective view of FIG. 9;

FIG. 11 is a front view of FIG. 9;

FIG. 12 is a rear view of FIG. 9;

FIG. 13 is a left side view of FIG. 9;

FIG. 14 is a right side view of FIG. 9;

FIG. 15 is a top plan view of FIG. 9; and,

FIG. 16 is a bottom plan view of FIG. 9.
